UNITED STATES PATENT OFFICE.

GEORGE R. McALLASTER, OF ROCHESTER, NEW YORK.

FOLDING BED.

Application filed July 12, 1920. Serial No. 395,601.

To all whom it may concern:

Be it known that I, GEORGE R. McALLASTER, a citizen of the United States, and resident of Rochester, in the county of Monroe and State of New York, have invented certain new and useful Improvements in Folding Beds, of which the following is a specification.

The present invention relates to folding beds and more particularly to the type in which the bed frame is mounted to swing upon a support from a position of use to an upright position, an object of this invention being to provide in a bed of this type a novel means of supporting a head piece which will serve as a rest for the head end of the mattress when the latter is thrown to an upright position. Another object of the invention is to provide a novel means for detachably supporting a weight at the head of the bed, provision also being made whereby the weight may be readily disconnected from the bed while at the same time it will be supported against accidental displacement during the ordinary use of the bed.

To these and other ends, the invention consists of certain parts and combinations of parts all of which will be hereinafter described, the novel features being pointed out in the appended claims.

In the drawings:

Fig. 1 shows the bed in side elevation and in lowered position;

Fig. 2 is a view in elevation of the head end of the bed while the latter is lowered;

Fig. 3 is an enlarged vertical section on the line 3—3, Fig. 2;

Fig. 4 is a fragmentary section on the line 4—4, Fig. 2;

Fig. 5 is a detail view of one of the weight supporting devices;

Fig. 6 is a view in elevation of the bed in folded position;

Fig. 7 is a fragmentary top view of the head end of the bed showing the latter in unfolded position; and

Fig. 8 is a fragmentary bottom view of the head end of the bed showing the latter in unfolded position.

The support on which the bed frame is pivotally mounted preferably embodies two upright angle bars 1 connected at their lower ends by a cross piece 2 and having a base frame connected thereto and comprising preferably side pieces 3 extending on opposite sides of the uprights, the rear ends of

said side pieces being connected by a cross piece 4. Braces 5 may connect the base frame with the uprights to strengthen the connection between the uprights and the base frame. A board 6 may rest on the side pieces 1 in front of the uprights to cover the lower portion of the frame, the lower end of this board being removably supported behind two blocks 7 secured to the forward ends of the side pieces 3.

The bed frame preferably embodies two side bars 8 formed of angle iron and supported on the upper ends of the uprights by a pivot rod 9 which connects the uprights 1 and projects beyond the same so that it may pass through the depending flanges of the side bars 8. The free end of the side bars 8 are connected by a cross piece 10 to which the bed fabric 11 is secured. At the inner or head end of the side bars, two spacing blocks 12 are provided, these blocks being formed of metal and each having a shoulder 13 on which a cross piece 14 of angle iron rests, this angle iron having the head end of the fabric 11 secured thereto. Bolts 15 extend through the cross piece 14 and the blocks 12, and are connected at their lower ends to the side bars 8 passing also through a cross piece 16 which connects the side bars 8 below the blocks. The flange of the cross piece 14 projects upwardly and in rear of this flange, a horn 17 is provided on each of the spacing blocks 12, these horns projecting above the fabric and having a head piece 18 fastened thereto in any suitable manner as by screws 19. This head piece serves for supporting the head end of the mattress when the bed is thrown to an upright position, the opposite ends of the mattress being secured in any suitable manner.

The spacing blocks 12 not only permit the plane of the fabric to lie at an angle to the plane of the side bars 8 in order that said side bars may be swung to a position beyond the vertical as shown in Fig. 6 so that there is no tendency for the bed to again swing to lowered position, but they also provide a space between the side bars and the mattress at the head end of the bed in which a counterbalancing means for the swinging end of the bed may be arranged. This counterbalancing means in this instance comprises two blocks 20 formed of cement or other suitable material and supported in line with each other between the cross pieces 16

and 14. For sustaining these blocks in their positions, strips 21 or other suitable connecting means are provided between the cross pieces 14 and 16. These strips 21 in 5 this instance are formed from strips of metal bent into U shape or form and each having at its ends, hooks 22, one of which engages the forward edge of the cross piece 14 and the other of which engages the 10 forward edge of the cross piece 16. It is apparent that the weights when the bed frame is thrown to an upright position will be sustained by these strips and will hold the hooked ends of the strips in 15 firm connection with the cross pieces whereas, when the bed is thrown to a position of use, the weight of the counterbalancing devices 20 will be sustained by the cross piece 16.

20 Any suitable means may be employed for supporting the swinging end of the bed frame. In this instance two legs 23 are employed pivoted at 24, said legs being longer than the uprights 1 so that the side bars 8 25 when lowered will lie at a slight angle to the surface on which the bed rests and in this way the fabric 11 will be substantially horizontal. A link 25, pivoted at 26 to each of the legs, has its rear end pivoted at 30 27 to one of the uprights, so that as the bed frame is swung to an upright position, the legs 23 will swing inwardly to the position indicated in Fig. 6.

From the foregoing it will be seen that 35 there has been provided a folding bed in which spacing blocks are employed at the head end of the bed for supporting the mattress fabric at an angle to the plane of the side bar, the spacing blocks also being utilized for supporting the head rest above the 40 fabric at the head end of the bed and being further utilized for providing a space at the head end of the bed in which counterbalancing means may be arranged. Two cross 45 pieces are provided at the head end of the bed between which the counterbalancing blocks are mounted, these cross pieces also serving as anchoring means for strips which will sustain the counterbalancing means in 50 position between the cross pieces when the bed frame is thrown to an upright position.

What I claim as my invention and desire to secure by Letters Patent is:—

1. In combination with a suitable support, a bed frame comprising side bars pivotally mounted on the support between their ends, a cross piece connecting the outer ends of said side bars, a pair of blocks secured to the inner ends of the side bars and each 60 formed with a seat, a cross piece secured to

the seats on both blocks, a mattress supporting fabric connecting the cross pieces, a second cross piece connecting the inner ends of the side bars below the other cross piece at the inner ends of the side bars, a counterweight supported by said second cross piece under the other of said cross pieces, and connecting means between the cross pieces having hooks engaging the forward edges of both cross pieces and assisting in supporting said counterweight upon the movement of the bed frame to upright position.

2. In combination with a suitable support, a bed frame comprising side bars pivotally mounted on the support between their ends, a cross piece connecting the outer ends of said side bars, a pair of blocks secured to the inner ends of the side bars and each formed with a seat, a cross piece secured to the seat on both blocks, a mattress supporting fabric connecting the cross pieces, a second cross piece connecting the inner ends of the side bars below the other cross piece at the inner ends of the side bars, a counterweight supported by said second cross piece under the other of said cross pieces, and U-shaped straps connecting the cross pieces and assisting in supporting said counterweight upon the movement of the bed frame to upright position.

3. In combination with a suitable support, a bed frame comprising side bars pivotally mounted on the support between their ends, a cross piece connecting the side bars at their outer ends, a pair of blocks resting upon the inner ends of said side bars and each formed with a seat, and a projection extending above the seat, a cross piece resting upon the seats of both blocks, bolts passing through the last mentioned cross pieces, the blocks and the side bars to secure said parts together, a head piece connecting said projections, and a mattress supporting fabric connecting the cross pieces.

4. In combination with a suitable support, a bed frame comprising side bars pivotally mounted on the support between their ends, a cross piece connecting the side bars at its outer ends, a cross piece at the inner ends of the side bars, a mattress supporting frame connecting the cross pieces, and means for supporting two counterweights in aligned relation under the cross piece at the inner ends of the side bars, said means permitting the independent removal of the counterweights by a movement of such counterweights toward the outer ends of said side bars.

GEORGE R. McALLASTER.
